UNITED STATES PATENT OFFICE.

ERASTUS WOODWARD, OF SOMERVILLE, MASSACHUSETTS, ASSIGNOR TO AMERICAN STAMPING MACHINE COMPANY, OF LYNN, MASSACHUSETTS, A CORPORATION OF MASSACHUSETTS.

INKING DEVICE FOR PRINTING AND MARKING MACHINES.

1,138,711.

Specification of Letters Patent. Patented May 11, 1915.

Application filed May 13, 1910. Serial No. 561,134.

To all whom it may concern:

Be it known that I, ERASTUS WOODWARD, of Somerville, in the county of Middlesex and State of Massachusetts, have invented 5 certain new and useful Improvements in Inking Devices for Printing and Marking Machines, of which the following is a specification.

My invention relates to improvements in 10 inking devices for stamping and marking machines, and its object is to provide automatic mechanism for normally covering and protecting the ink to exclude the dirt and dust and prevent evaporation when the device is not in use, and to automatically uncover and operate the device when it is necessary to ink the type.

The important feature of this device is the 15 provision of mechanism for automatically shifting the position of the ink roll at each inking operation to expose and contact a different portion of the ink roll with the type at each inking operation.

Another feature of this device is the utilization of an absorbent pad which carries 20 the ink and which contacts with and wipes the ink roll, thereby feeding the ink evenly to the roll and preventing an excess accumulation of ink thereon.

In the accompanying drawings which 25 illustrate a construction embodying my invention Figure 1 is a side elevation of the device operating in conjunction with the marking machine shown and described in my application Serial Number 527,633, the parts being shown in normal or operating position. Figs. 2 and 3 are similar views, showing the consecutive positions and operations of the inking mechanism prior to each 30 impression of the type head. Fig. 4 is a front elevation of Fig. 1. Fig. 5 is a similar view to Fig. 4 with the type head and an inking device removed with parts broken away to more clearly illustrate the mechanism for connecting the inking device with the machine. Fig. 6 is a top plan view of 35 the inking device with the cover and automatic shutter removed. Fig. 7 is a vertical cross section through the center of the device and Figs. 8 and 9 are respectively the covering and automatic shutter for covering the same.

Like letters of reference refer to like parts throughout the several views.

Referring to the drawings, Figs. 1, 2, 3, 4 and 5 C represents the supporting frame of 55 the machine described in my application Serial Number 527,633 which frame carries the rock shaft D mounted in the bearing C' in the upper part thereof, said shaft having 60 secured to its outer end by set screws D² the yoke arm D', which carries mounted on its free end the inking mechanism E.

The rock shaft G is mounted in the bearing C² and carries the lever or type arm G' 65 secured thereto by the set screw G². The type head J is secured by clamp screw J² to the outer end of type arm G'. The rock shafts D and G are thrown into coöperation with and drawn by a suitable clutch at each 70 operation as described in the above named application.

H' represents the work supporting table upon which the articles are placed to receive the impression of the type head J.

The type head J (see Figs. 1 and 4) is of 75 the usual construction, consisting of the ring type disks J³ rotatably mounted on a central shaft J⁴ which is journaled in the type head J. The knob J⁵ is secured to the outer projecting end of shaft J⁴ and is for the purpose of manually adjusting and frictionally turning whichever of the said type disks that may be released by suitable pawls J¹¹ pivoted on the shaft J⁶ so that the required 80 figures or characters located on the periphery of the disks J³ may be removed into alignment for making an impression on the articles to be marked.

The inking mechanism E (see Figs. 6, 7, 8 and 9) comprises the casing E' which carries a hollow supporting stem E² mounted within the clamp D³ to the lower end of the yoke arm D'. The screw D⁴ is adapted to clamp the casing E' in position on said yoke 95 arm D' (see Fig. 1).

In the casing E' is a shaft E⁵ which carries the ink-roll E⁶. Mounted inside and at the rear of the casing E' is an absorbent composition E⁷ preferably felt, which absorbs and retains the ink. A felt wiper E⁸ is fastened at one end upon a pin E⁴ and left free at its opposite end. This wiper is located between the composition E⁷ and the roll E⁶, being in contact with and extending 100 around the greater portion of the periphery of said roll E⁶. This serves to prevent the composition E⁷ from getting beneath and 105

clogging the roll E⁶ when the same turns, and also serves to distribute the ink evenly upon the outer periphery of the roll.

E³⁰ is a cover having an aperture therein 5 E³¹ to give access to the ink roll E⁶, said cover being secured to the upper part of the casing E¹ by means of screws E³².

To prevent evaporation of the ink when the type is not in contact with the ink roll 10 E⁶ an automatic shutter E¹⁸ is provided which is reciprocally mounted upon the top of the cover E³⁰ and normally closes the aperture E³¹. This shutter E¹⁸ carries stem E¹⁵ extending through the hollow stem E², 15 the portion of said stem E¹⁵ projecting through the hollow stem E² carrying a notch E¹⁶ which engages with the spring latch E¹⁷ (see Figs. 1 and 5). This latch E¹⁷ is pivoted at E¹⁸ in a slot in the lower end of the 20 hanger E¹⁹ the upper end of which hanger is loosely mounted on the hub E²⁰ in the upper end of the yoke arm D'. The spring E²¹ secured to the lower end of the hanger E¹⁹ acts against the extension E²² of the spring 25 latch E¹⁷ to hold said latch in position within the notch E¹⁶.

E²³ and E²⁴ are stops carried by hanger E¹⁹ on respectively opposite sides of the rib E²⁵ on the main frame C.

30 The operation of the shutter is shown in Figs. 1, 2 and 3, Figs. 2 and 3 showing the shutter withdrawn while the type is being inked and Fig. 1 showing the shutter closed, entirely covering the ink roll E⁶ when the 35 type is not being inked. On one end of the shutter E¹⁸ is a rack E³³ which meshes with a pinion E³⁴ loosely mounted over one end of the shaft E⁶.

E³⁵ is a spring pawl secured to the pinion 40 E³⁴ by a screw E³⁶, said pawl adapted to engage with a ratchet wheel E³⁷ secured to the extreme outer end of the shaft E⁶. When the shutter E¹⁸ is opened the rack E³³ moves the pinion E³⁴ upon the shaft E⁶ causing the 45 pawl E³⁵ to engage one of the teeth of the ratchet wheel E³⁷, causing the ink roll E⁶ to be turned a portion of a revolution, which moves into position for contacting with the type a portion of the ink roll which had previously been in engagement with the wiper E³. When the shutter is closed the pinion 50 E³⁴ is operated in the reverse direction while the pawl E³⁵ nearly slides over the teeth of the ratchet wheel E³⁷.

55 The operation is as follows: With the parts in a normal or non-operating position as shown in full lines in Fig. 1, the operator desiring to print or stamp the articles places the same on the work supporting table H', and presses the foot pedal which throws into action with the driving power the clutch which has been fully described in my application hereinbefore referred to, which action of the clutch operates to move the rock shaft D, moving the yoke arm D' and

inking mechanism E outward and upward (see Fig. 2) until the stop E²⁴ has engaged the rib E²⁵ which stops any further movement of the hanger E¹⁹, causing the shutter E¹⁸ to be withdrawn and exposing the ink roll E⁶ which in the meantime has been moved as hereinbefore described, exposing a freshly inked portion of the ink roll E⁶. A further movement of the yoke arm D' causes the roll to contact with one edge of the type on type head J. In the meantime the rock shaft G is operated to move the type head J upward together with the inking mechanism E, continued relative movement of the type head J and the inking 70 mechanism E causing the ink roll E⁶ to roll along the face of the type while the rack E³³ continues to operate the pinion E³⁴ and roll E⁶ until the type head J draws away from the ink roll E⁶ as shown in Fig. 3. The 75 type head J now remains momentarily stationary while the inking mechanism E is operated by the rock shaft D to draw away from the type head and return to its normal position as shown in Fig. 1. In the meantime after the inking mechanism E has moved out of the way of the type head J the rock shaft G causes the type head J to be moved downward to the dotted line position 80 shown in Fig. 1, marking the article located 85 on the table H', while the continued movement of the machine causes the type head J to be moved upward to its normal position as shown in full lines Fig. 1. Upon the return movement of the inking mechanism E 90 as described the stop E²³ engages the rib E²⁵, stopping the movement of the hanger E¹⁹, thereby closing the shutter E¹⁸. The 95 machine is now at rest in its normal position with the inking mechanism E covered, 100 which prevents any evaporation of the ink.

I do not limit myself to a step movement of the ink roll E⁶ to consecutively expose a freshly inked portion of the same for inking the type, as the roll E⁶ may be oscillated 110 sufficiently to freshly ink the portion of the roll which engages the type at each operation.

Having thus described my invention and set forth a construction embodying the same 115 what I claim as new and desire to secure by Letters Patent of the United States is:

1. In a device of the character described, a type head, an inking roll adapted to engage and ink the type carried on said head, 120 means for inking said type previous to each impression thereof, an operating arm independent of said type head for carrying said inking roll and adapted to operate said roll whereby the same is moved across the 125 type to ink the same and subsequently to withdraw from contact with the type and out of the path thereof on its return movement to permit the impression of said type head, mechanism for operating said type 130 head, mechanism for operating said type 135

head independently of the mechanism which operates said inking roll operating arm.

2. In a device of the character described, a type head, an inking roll adapted to engage and ink the type carried on said head, means for inking said type previous to each impression thereof, an operating arm independent of said type head for carrying said inking roll and adapted to operate said roll whereby the same is moved across the type to ink the same and subsequently to withdraw from contact with the type and out of the path thereof on its return movement to permit the impression of said type head, mechanism for operating said type head independently of the mechanism which operates said inking roll operating arm, and mechanism for automatically shifting the position of said roll at each inking operation whereby a different portion of said roll is engaged by said type previous to each impression.

3. In a device of the character described, a type head, an inking device comprising an inclosed holder, an inking roll mounted in said holder, an absorbent material carried in said holder for retaining and feeding the ink to said roll, an automatic shutter adapted to expose said roll to ink the type and to cover said roll when the same is not in inking operation, and mechanism operated by said shutter when opening to move said inking roll previous to the inking of said type.

35. 4. In a device of the character described, a type head, an inking device comprising an inclosed holder, an inking roll mounted in said holder, an absorbent material carried in said holder for retaining and feeding the ink to said roll, a shutter normally inclosing said inking roll, and mechanism operated by said shutter when opening to move said inking roll previous to the inking of said type, said mechanism adapted to permit the closure of said shutter after the inking of said type without moving said roll.

5. In a device of the character described, a type head, an inking device carrying an inking roll adapted to engage and ink the type carried on said type head, an absorbent material for retaining and feeding the ink to said roll, and yielding means for holding said absorbent material in contact with said roll.

55. 6. In an inking device, the combination with a swinging type head, of an inking roll mounted in a holder, an absorbent material mounted in said holder and in contact with said roll for holding and feeding the ink to said roll, mechanism for operating said holder and said roll to ink the type with each impression, and an automatic shutter normally covering said holder and said roll

and adapted to automatically open to expose said roll to permit the inking of the type with each impression thereof.

7. In an inking device, the combination with a swinging type head, of an inking roll mounted in a holder, a wiper mounted in said holder and in contact with said roll and adapted to feed ink to the same, said wiper being fixed at one end to prevent displacement of the same when said roll is operated, means for operating said holder and said roll to ink the type with each impression thereof, and an automatic shutter normally covering said holder and said roll and adapted to be automatically opened prior to each impression to expose said roll for inking the type.

8. In a printing and marking machine, a type carrier, mechanism for operating said type carrier, an inking pad, and a closure carried with said pad adapted to be operated to expose said pad during the inking of the type.

9. In a printing and marking machine, a type carrier, mechanism for operating said type carrier, an inking roll for inking the type, a holder for said roll, an absorbent material on said holder and in contact with said roll for retaining the ink and feeding the same to said roll, and an automatic shutter normally inclosing said holder and said roll and adapted to be operated to expose said roll to permit the inking of the type.

10. In a printing and marking machine, a type carrier, mechanism for operating said type carrier, an inking roll for inking the type, a holder for said roll, an absorbent material mounted in said holder and in contact with said roll for retaining the ink and feeding the same to said roll, means for intermittently turning said roll, and an automatic shutter normally inclosing said holder and said roll and adapted to be operated to expose said roll to permit the inking of the type.

11. In an inking device, an inclosed holder, a roll mounted in said holder and having a portion of its periphery adapted to be exposed, an absorbent material mounted in said holder in contact with said roll for holding and feeding the ink to said roll, and an automatic shutter normally inclosing said holder and said roll and adapted to be operated to expose said roll to permit the inking of the type.

In testimony whereof, I have signed my name to this specification in the presence of two subscribing witnesses, this third day of April A. D. 1910.

ERASTUS WOODWARD.
